CLAIM

We claim the ornamental design for a hand held domed and footed wheel and rim cover, as shown and described.

DESCRIPTION

FIG. 1 is a perspective view of a hand held domed and footed wheel and rim cover showing our new design;

FIG. 2 is a front elevational view thereof;

FIG. 3 is a rear elevational view thereof;

FIG. 4 is a right side elevational view thereof, the left side elevational view being a mirror image thereof; and

FIG. 5 is a top plan view thereof, the bottom plan view being identical thereto; and,

FIG. 6 is a reduced perspective view showing the hand held domed and footed wheel and rim cover in use; the broken lines show environmental structure for illustrative purposes only and form no part of the claimed design.
